UNITED STATES PATENT OFFICE.

ALFRED L. SCHWENKE, OF PORTLAND, MAINE.

SNOW LOADER.

Application filed August 31, 1925. Serial No. 53,503.

My invention involved herein relates to the removal of snow from streets and particularly to its transportation to other points where it can be dumped. The problem of handling snow in metropolitan districts particularly, has become a very serious one not only on account of the expense involved in handling it but by reason of the obstruction of traffic and the delays in business.

10 In northern climates if snow is not removed from the streets with considerable promptness it is very apt to become packed or frozen especially where there is considerable traffic which tends to compact, rut and otherwise put the snow in condition where it is difficult to remove even with great labor.

My invention therefore contemplates means for very rapidly taking up the snow so that it can be removed before it has 20 reached a condition as above suggested. To this end I provide a mobile apparatus capable of very rapidly taking up the snow in continuous strips or ridges whereby streets may be cleared promptly and gutters opened 25 and the thoroughfare made available for traffic. Various features of my invention are capable of somewhat varied embodiment, but for the purposes of disclosure herein I have shown a machine well adapted to practical 30 use and capable of construction and operation at reasonable cost. Such I have shown in the accompanying drawings, to which I shall make reference by the use of characters similarly applied throughout specification and drawings to indicate corresponding 35 parts. In the drawings:

Fig. 1 is a side elevation of apparatus in accordance with my invention.

Fig. 2 a plan view thereof.

40 Fig. 3 is a view of the shovel member.

Fig. 4 a section on the line 4—4, of Fig. 1.

Fig. 5 is a plan view partly in section on the line 5—5, of Fig. 1.

45 Fig. 6 is a partial vertical section of the forward end of the machine, and

Fig. 7 a plan view of the upper drive connection for the conveyor screw.

In constructing my apparatus I preferably provide a frame or body composed of longitudinal beams 1 covered by a forward platform or deck 2 and cross coupled at the rear by a cross beam 3 which is detachably pinned to the end of the longitudinal beam 1. The frame is preferably mounted on rear 55 runners 4 and a pair of forward runners 5 which are swiveled as at 6 in a suitable head

bearing in which they are free to turn subject to the limitations of the chain 7. To the rear of the deck 2 the frame is open for the reception of a tractor, as indicated at T 60 in dotted lines in Figs. 1 and 2. Such a tractor when admitted through the rear cross head 3 is shackled to it as at 8 for draft purposes. I preferably carry on the rear of the machine a scraper 9 drawn on links 10 for 65 leveling off the snow after the plow has cleared the way.

Mounted on the forward deck 2 is a frame comprising a vertical column 11 and a forwardly extending member 12 which rests on a turntable 13 supported on rollers 13¹ which bear on the deck 2. The turntable 13 has a central bearing 14 so that the entire superstructure turns on 14 as a pivot, the rear column 11 being provided with a roller 11¹ 70 so that it is free to swing while supporting the rear of the superstructure.

To the forward edge of the member 12 of this superstructure, which edge is inclined at about 45°, I attach a conveyor tube 15 75 which extends downwardly adjacent to the normal street level with just sufficient clearance at its lower end so that when the scoop 16 is tipped up as shown in dotted lines in Fig. 1, the machine can be moved freely 80 from place to place. The scoop 16 is pivoted to the chute 15 as at 16¹ and is provided with a segment and pawl 16² for locking it in place when in operating position.

Journaled in suitable bearings at either 90 end of the tube 15 is a conveyor shaft 17 carrying a spiral blade 18. At its lower end it is provided with a propeller like device 19 adapted to break up the snow and present 95 it to the conveyor by which it is carried upward to the upper end of the superstructure. The propeller shaft 17 is driven by a gear 20 which meshes with a pinion 21 on a shaft 22 which in turn is driven by a pair of gears 23, 24, the latter being on a shaft 25. The shaft 25 has at its lower end a large bevel gear 26 which is driven by a pinion 27 on a shaft 28. This shaft is connected by a universal joint connection 29 with the end of the crank shaft 30 of the tractor T. The tractor T therefore not only moves the device on its runners on the street, but provides the power for the conveyor.

On the opposite end of the shaft 28 from the pinion 27 is a pinion 31 geared to a crank shaft 32 on which there is a crank 33 for cranking the motor of the tractor when

the tractor is in position within the frame of the machine.

On the shaft 22 are a pair of pinions 34, 35, which drive a countershaft 36 which is connected by chain and sprocket to a conveyor shaft 37 in a trough 38. The pinions 34, 35, constitute a reversing mechanism for the shaft 36 by any suitable reversing lever (not shown). The large gear 26 is free on the shaft 25 and controlled by a clutch 39 operated by a hand lever 40. The conveyor drives may therefore be stopped or started independently of the tractor.

In operation, with the shovel or scoop 16 in the position shown in full lines in Fig. 1, the machine may be advanced along the street taking up the snow that is to be removed. If the snow fall is relatively light and not of too great depth, the street may be first plowed to throw the snow up in ridges, preferably of about the width of the scoop. In this way a light fall of snow may be very rapidly taken up without needless trips back and forth or in case of an impending blizzard, the snow can be taken up as it falls.

As the snow enters the scoop it has a tendency to compact against the conveyor tube 15 which approaches it at an angle. At this point it is beaten apart and thrown upwardly against the lower part of the conveyor blade 18 which carries it up and drops it into the trough 38 in which the transverse conveyor 38¹ is working. As will be noted in the plan view in Fig. 2, the trough 38 is adapted to receive at either end a chute 41 so that the snow can be discharged laterally of the machine either into other vehicles for taking it away, or to the side of the road, if such should be expedient for the purpose, the transverse conveyor shaft 37 being driven in the direction desired by the reversing gears 34, 35.

As will be seen from the foregoing, such a machine is simple and inexpensive to build and can be produced in sufficient numbers to deal with even more extreme snow conditions with which the street department may have to contend. They are easy to operate and inexpensive to maintain. The adjustment of the turn table 13 permits the scoop 16 to work either directly in front of the machine,

as shown in full lines in Fig. 2, or to work at one side as shown in dotted lines. This is often very convenient in the case of heavy snows or partly bare ground, as it permits the machine to operate on runners which in most climates requiring apparatus of this sort are more satisfactory than wheels. It could, of course, be mounted on wheels or trucks, if desired.

The type of tractor indicated at T may of course and probably would be considerably varied and connections modified to suit the type. Various other modifications might be made in the structure of the device, all without departing from the spirit of my invention if within the limits of the appended claims.

What I therefore claim and desire to secure by Letters Patent is:

1. In a snow remover, a supporting frame, a head pivoted thereon for rotation on a vertical axis, an inclined conveyor chute, a scoop at the end of said chute, a spiral conveyor in said chute, a cross conveyor adjacent the upper end of the first named conveyor, and means for driving said conveyors, including means for reversibly driving the cross conveyor.

2. In a snow remover, a supporting frame, a head pivoted thereon for rotation on a vertical axis, an inclined conveyor chute, a scoop at the end of said chute, a spiral conveyor in said chute, a bladed snow breaker at the lower end of said conveyor disposed adjacent the rear of the chute, a cross conveyor adjacent the upper end of the first named conveyor, and means for driving said conveyors, including means for reversibly driving the cross conveyor.

3. In a snow remover, a supporting frame, a head pivoted thereon for rotation on a vertical axis, an inclined conveyor chute, a scoop at the end of said chute, a conveyor in said chute, a cross conveyor adjacent the upper end of the first named conveyor, and means for driving said conveyors, including a terminal connection alignable with the engine shaft of a power machine disposed in motive relative thereto.

In testimony whereof I affix my signature.

ALFRED L. SCHWENKE.
